(57) **CLAIM**

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a face view of a first image in a sequence of a first embodiment of a design for a display screen or portion thereof with animated graphical user interface, in color; FIG. 2 is a face view of a second image thereof; FIG. 3 is a face view of a third image thereof; FIG. 4 is a face view of a fourth image thereof; FIG. 5 is a face view of a fifth image thereof; FIG. 6 is a face view of a sixth image thereof; FIG. 7 is a face view of a first image in a sequence of a second embodiment of a design for a display screen or portion thereof with animated graphical user interface, in greyscale;

FIG. 8 is a face view of a second image thereof;

FIG. 9 is a face view of a third image thereof;

FIG. 10 is a face view of a fourth image thereof;

FIG. 11 is a face view of a fifth image thereof; and,

FIG. 12 is a face view of a sixth image thereof.

The appearance of the animated user interface sequentially transitions between the images shown in FIGS. 1-6 and between the images shown in FIGS. 7-12. The process or period in which one image transitions to another forms no part of the claimed design.

The line-dot-line showing of a display screen or portion thereof forms no part of the claimed design. The text shown in broken line in FIGS. 1-12 forms no part of the claimed design.
